PRESSER FOOT FOR SEWING MACHINES

Otto Mohn, Stuttgart, Germany, assignor to
Mauser-Werke A.-G., Oberndorf-on-the-Nec-
kar, Germany, a joint-stock company of Ger-
many

Application April 27, 1937, Serial No. 139,313
In Germany April 16, 1936

4 Claims. (Cl. 112—235)

This invention relates to a presser foot for sewing machines of any desired design, and refers to a presser foot having resilient runners which are capable of yielding upon the occurrence of transverse seams or other thickened portions of the material so as to permit of a proper feeding of the material.

It has already been proposed to employ, when transverse seams are to be dealt with, presser feet which are furnished with resilient side portions guided in pins. Presser feet having side portions are also known which are rotatable about a stud and in which the side portions are pressed downwards by a spring. These known arrangements are accompanied by the disadvantage that upon the occurrence of transverse seams the material situated in front of or behind the seam is not pressed down sufficiently owing to a lifting of the side portions, so that a proper feeding of the material is unable to take place. It has also already been proposed to secure on the presser foot resilient bars by means of screws and rigidly attached to the presser foot and which are merely hollow at the centre, so that they are resilient at this point only. The attachment of these bars at the front of the presser foot takes place by means of a normal flat-headed screw, whilst at the rear end of the presser foot an abutment screw enables the end of the bar to yield longitudinally. Owing to the fact that the bars bear tightly against the presser foot at the front and the rear they are unable to yield at these points.

These disadvantages associated with the known arrangements are avoided by the invention. According to the invention, there are provided on both sides of the presser foot to the right and the left resilient runners, each of which is secured to the presser foot by means of a screw. Owing to the fact that these runners have an intermediate space which is greater than the thickness of the lower foot portion these runners are resilient in themselves at all points and are accordingly readily able to adapt themselves at all points to the piece of work. Moreover since the runners each consist of one piece and their attachment is effected in each case solely by means of one screw at the centre of the presser foot the resiliency of the runners is equal in front of and behind the point of attachment and accordingly at all points.

In order to afford the runners a lateral guiding and accordingly to prevent a rotation of the same the bottom portion of the presser foot is reduced along the runners.

An additional advantage of the arrangement according to the invention consists in the fact that by reason of the resilient runners there is also a compensation of differences in the elevated position of the material feeder.

Any desired additional resiliency may be obtained by differences in the size of cross-section of the runners or by the provision of additional springs on the upper side or lower inner side of the runners, so that the possibility exists of extensive adaptation to any kind of sewing.

An example of the invention is illustrated in the drawing in adaptation to a two-needle presser foot. The invention is not limited to this form of embodiment, but may be employed on any kind of sewing machine. In the drawings

Fig. 1 is an elevational view of the presser foot, the material feeder and the throat plate, the feeder being situated in the operative position.

Fig. 2 is a plan view of the presser foot,

Fig. 3 a front view of Fig. 1, and

Fig. 4 an elevational view of the presser foot in the unloaded condition.

Figs. 5 to 8 are elevational views of the presser foot, the material feeder and the throat plate with pieces of work having a transverse seam in different positions, viz. in

Fig. 5 at the commencement of the presser foot, in

Fig. 6 at the centre of the presser foot, i. e., below the point of attachment of the runners, in

Fig. 7 at the end of the presser foot, and in

Fig. 8 without transverse seam.

Fig. 9 is a vertical section along the line A—A in Fig. 1.

To the bottom portion *a* of the presser foot *b* there are screwed in each case to the right and the left by means of the screws *c* and *d* a runner *e* and *f*. Each runner consists of one piece and the two ends are superimposed at the point of attachment (compare Figs. 1 and 2). These runners are so dimensioned that their intermediate space *g* (Fig. 9) is greater than the thickness *h* of the lower portion of the presser foot, so that the runners are capable of resiliency at all points dependent on the position of the transverse seam (Figs. 5 to 7). To permit of lateral guiding of the runners, and accordingly to prevent a rotation of the same, the lower portion *a* of the presser foot is reduced at *i* corresponding to the thickness of the material of the runners, so that the underside of the presser foot constitutes a flat surface. Further, the upper side of the lower foot portion is reduced at *k*.

Having now particularly described and ascertained the nature of my said invention, and in what manner the same is to be performed, I declare that what I claim is:

- 5 1. A presser foot for sewing machines comprising a bottom portion, at least one resilient runner mounted on the said bottom portion, the said runner constituting a complete resilient band entirely embracing the bottom portion, and 5
- 10 10 a single fastening means connected to the runner and inserted into the upper side of the bottom portion.
- 15 2. A presser foot for sewing machines comprising a bottom portion, a resilient runner 15 mounted at each side of the bottom portion, each of the runners being in the form of a complete resilient band entirely embracing the bottom portion, and a single fastening means connected to each runner and inserted into the upper side of 20 the bottom portion.
- 20 3. A presser foot for sewing machines comprising a bottom portion having at least one off-set part on the upper and lower sides thereof, at

least one resilient runner mounted on the bottom portion adjacent the off-set parts, the said runner being in the form of a complete resilient band entirely embracing the bottom portion, and a single fastening means connected to the bottom portion and securing the runner on the bottom portion, the off-set parts guiding the said runner laterally on the bottom portion.

4. A presser foot for sewing machines comprising a bottom portion, and at least one resilient runner mounted on said bottom portion and constituting a complete resilient band entirely embracing the bottom portion but spaced from the bottom surface of the bottom portion in the non-contacting position of the presser foot, said runner being secured on the upper surface of the bottom portion to prevent travel of the runner on the bottom portion when material being sewed is fed under the presser foot and to permit the runner to yield only in the vertical 20 direction.

OTTO MOHN.
